US00D850035S

(12) **United States Design Patent** (10) **Patent No.:** **US D850,035 S**
(45) **Date of Patent:** **** May 28, 2019**

(54) **WASHING MACHINE**

(71) Applicant: **SAMSUNG ELECTRONICS CO., LTD.**, Suwon-si, Gyeonggi-do (KR)

(72) Inventors: **Sanghun Yoon**, Seoul (KR); **Yuna Park**, Seoul (KR); **Myunggyu Kim**, Seoul (KR); **Ahjung Joo**, Seoul (KR)

(73) Assignee: **SAMSUNG ELECTRONICS CO., LTD.**, Gyeonggi-Do (KR)

(**) Term: **15 Years**

(21) Appl. No.: **29/648,688**

(22) Filed: **May 23, 2018**

Related U.S. Application Data

(63) Continuation of application No. 29/607,235, filed on Jun. 12, 2017, now Pat. No. Des. 824,123, which is a continuation of application No. 29/590,790, filed on Jan. 13, 2017, now Pat. No. Des. 825,867.

(30) **Foreign Application Priority Data**

Nov. 29, 2016 (KR) 30-2016-0057634

(51) **LOC (11) Cl.** **15-05**

(52) **U.S. Cl.**

USPC **D32/6**

CLAIM

We claim the ornamental design for a washing machine, as shown and described.

DESCRIPTION

FIG. 1 is the front perspective view of a washing machine showing our new design;

FIG. 2 is the front view thereof;

FIG. 3 is the rear view thereof;

FIG. 4 is the left-side view thereof;

FIG. 5 is the right-side view thereof;

FIG. 6 is the top view thereof; and,

FIG. 7 is the bottom view thereof.

The broken lines in the figures depict environmental subject matter and form no part of the claimed design.

1 Claim, 7 Drawing Sheets
